UNITED STATES PATENT OFFICE.

LOUIS WILPUTTE, OF NEW ROCHELLE, NEW YORK, ASSIGNOR OF TWO-THIRDS TO
ALICE A. WILPUTTE, OF NEW ROCHELLE, NEW YORK.

REGENERATIVE COKE-OVEN.

1,360,610.

Specification of Letters Patent. Patented Nov. 30, 1920.

Application filed September 30, 1918. Serial No. 256,201.

To all whom it may concern:

Be it known that I, LOUIS WILPUTTE, a citizen of the United States, and resident of New Rochelle, in the county of Westchester 5 and State of New York, have invented certain new and useful Improvements in Regenerative Coke-Ovens, of which the following is a specification.

My present invention relates particularly 10 to regenerative coke ovens of the type heretofore devised by me in which a plurality of regenerators arranged side by side beneath and extending transversely to the lengths of the coking chambers, are supplied with air 15 to be preheated by means of one or more metallic air supply pipes, each formed with a discharge orifice for each of the plurality of regenerators, the different discharge orifices being carefully proportioned to insure 20 the proper supply of air through each pipe to each of the plurality of regenerators served by the pipe. In coke ovens of this type each air pipe is received in a corresponding channel, generally rectangular in 25 cross section, which is formed in the brick-work under the regenerators, served by the supply pipe which is inserted in the channel. The top wall of each channel is formed with ports opening into the different regenerators, 30 and with which the discharge orifices of the corresponding pipe register. In an ordinary by-product coke oven, these channels, which extend into the oven structure from the side of the oven battery, are in the neighborhood 35 of twenty feet long. The iron air supply pipes are ordinarily made removable so that the discharge orifices may be reamed out or partially plugged to change this distribution of air to the different regenerators if, and 40 when this becomes necessary.

Practical considerations, which those familiar with the furnace art will readily understand, make it necessary to provide some clearance between the walls of the channel and the external wall of the air supply pipe in order to permit the ready removal and insertion of the latter not only when the structure is in its initial condition, but also after due to thermal expansion, etc. For example, it has been common practice to make 45 brickwork channel seven and one-half inches square in cross section and use an iron air supply pipe of an external diameter of six and five-eighths inches. This permits a possible by-passing, or cross-flow, from one of 50 55

the ports in the top wall of the channel to an adjacent port, through the clearance space between the periphery of the iron pipe and the inner walls of the masonry channel.

While this cross-flow has not given rise to 60 any real difficulty, the tendency to cross-flow is one which it is desirable to eliminate, and the primary object of the present invention is to provide simple and effective means for substantially eliminating the tendency to 65 cross-flow through the clearance space between the metallic pipe and the inner walls of the brickwork channel. This object is attained in accordance with the present invention by providing means for forcing the 70 metallic air pipe into contact with the top wall of the brickwork channel after the pipe is inserted in the channel. In the preferred manner of carrying out the invention I attach to the iron pipe, which is circular in 75 cross section, lugs or projections which are received in one of the lower corners of the brickwork channel when the pipe is being inserted in, or removed from the channel, but which are brought beneath the center of the 80 pipe by a partial rotation of the latter, after the pipe has been fully entered in the channel.

The various features of novelty which characterize my invention are pointed out 85 with particularity in the claims annexed to and forming a part of this specification. For a better understanding of the invention and the advantages possessed by it, reference should be had to the accompanying drawings 90 and descriptive matter in which I have illustrated and described a preferred embodiment of my invention.

Of the drawings, Figure 1 is a vertical section of a portion of a regenerative coke 95 oven.

Fig. 2 is a partial section on line 2—2 of Fig. 1, showing the air pipe in its operating position.

Fig. 3 is a view taken similarly to Fig. 2 100 showing the pipe in position occupied by it when being inserted and removed from the oven structure.

Fig. 4 is a view taken similarly to Fig. 2 105 illustrating a slight modification.

In the drawings A represents a portion of a regenerative coke oven having longitudinal regenerators corresponding in number to the number of heating flues in the heating walls (not shown) with which the 110

regenerators are connected, the different flues in each of the heating walls above the regenerators being connected to different regenerators. This type of oven is disclosed 5 in my prior Patents No. 1212866 granted January 16, 1917, and No. 1253760 granted January 15, 1918.

Beneath the regenerators are formed one or more brickwork channels C, running 10 transversely of the regenerators, into the oven structure from the opposite side edges of the battery to the center of the latter. Ports D in the top wall of each channel C open, one each, into each of the regenerators 15 B above the channel. Each channel C receives an iron air supply pipe E formed with ports E¹ which register with the brick-work ports D when the air pipe is in its operating position as shown in Figs. 1 and 2. 20 The brickwork channel C is generally rectangular in cross section, though advantageously as shown, a shallow groove C may be formed in the top wall of each channel C to receive the upper portion of the corresponding pipe E. The air pipe E is circular in cross section and for reasons already explained, the external diameter of the air pipe is less than the width and depth of the channel C in which it is received. 25 The pipe E has attached to it lugs or camming parts E², as shown in Figs. 1, 2 and 3 in the form of bent arms formed out of metal plate, and each attached at one end to the pipe E as by spot-welding it to the latter. The free end of each arm E² projects away from the outer surface of the pipe E. The parts are so proportioned that the pipe E may be axially inserted in and removed from its channel C, when the pipe is 30 rotated about 45 degrees or so, away from the position in which the ports E¹ register with the ports D. In this angular adjustment of the pipe E, shown in Fig. 3, the arms E² are received in one of the lower corners of the channel C, while the body of the pipe rests upon the bottom wall of the channel. After the pipe E is thus inserted in the channel C, the pipe is rotated to bring it 35 into the position shown in Figs. 1 and 2. 40 This rotation of the pipe E brings the arms E² between the under side of the pipe and the bottom wall of the channel C and thereby cams the pipe snugly up against the top wall of the channel. This effectually eliminates the possibility of any appreciable flow 45 through the space in the channel C external to the pipe E, from one to another of the ports D. By forming the arms E² of metal plate as shown in Figs. 1, 2 and 3, these 50 arms are given sufficient flexibility to compensate for irregularities in the brickwork. Where such irregularities may not require the use of flexible arms E², the latter may be replaced by solid lugs E²⁰, as shown in 55 Fig. 4. The lug E²⁰ may be secured to the 60

pipe E by spot-welding or in any other suitable manner.

While in accordance with the provisions of the statutes, I have illustrated and described the best forms of my invention now 70 known to me, it will be apparent to those skilled in the art that changes may be made in the form of the apparatus disclosed without departing from the spirit of my invention as set forth in the appended claims, and 75 that certain features of my invention may sometimes be used to advantage without a corresponding use of other features.

Having now described my invention, what I claim as new and desire to secure by Let- 80 ters Patent is:—

1. In a regenerative furnace, comprising a group of regenerator chambers arranged side by side and a brickwork channel alongside the regenerator chambers and ports leading from the different regenerator chambers to said channel at one side of the latter, and having a removable metallic pipe loosely received in said channel and formed with orifices adapted to register with said ports, the improvement consisting of coöperating pipe and channel parts automatically coöperating to cam the pipe laterally in said channel into snug engagement with the side of the channel at which said ports 95 open as said pipe is moved in said channel to bring said orifices into registry with said ports.

2. In a regenerative furnace comprising a group of regenerator chambers arranged 100 side by side and a brick-work channel alongside the regenerator chambers and ports leading from the different regenerator chambers to said channel at one side of the latter, and having a removable metallic pipe 105 loosely received in said channel and formed with orifices adapted to register with said ports, the improvement which comprises projections rigidly secured to the pipe and adapted to engage with the wall of the channel and force the pipe laterally into snug engagement with the side of the channel at which said ports open.

3. In a regenerative furnace comprising 115 a group of regenerator chambers arranged side by side and a brick-work channel alongside the regenerator chambers and ports leading from the different regenerator chambers to said channel at one side of the latter, and having a removable metallic 120 pipe loosely received in said channel and formed with orifices adapted to register with said ports, the improvement which comprises projections secured to the pipe and adapted to engage with the wall of the 125 channel and force the pipe laterally into snug engagement with the side of the channel at which said ports open, as said pipe is rotated from one position in which said orifices do not register with said ports into 130

a second position in which the orifices register with said ports.

4. In a regenerative furnace comprising a group of regenerator chambers arranged side by side and a brickwork channel alongside the regenerator chambers and ports leading from the different regenerator chambers to said channel at one side of the latter, and having a removable metallic pipe loosely received in said channel and formed with orifices adapted to register with said ports, the improvement which comprises projections secured to the pipe and adapted to engage with the wall of the channel and force the pipe laterally into snug engagement with the side of the channel at which said ports open as said pipe is rotated from one position in which said orifices do not register with said ports into a second position in which the orifices register with said ports. 35
- 10 6. In a regenerative coke oven comprising a plurality of regenerators arranged side by side and formed with a brickwork channel beneath the regenerators, polygonal in cross section, and having ports leading through its top wall to the different regenerator chambers and having a removable metallic pipe, circular in cross section and loosely received in said channel and formed with orifices adapted to register 40 with said ports, the improvement which consists in projections secured to said pipe and adapted to slide in a lower corner of said channel as said pipe is inserted in and removed from said channel, and adapted to 45 engage the bottom of the channel and cam the pipe against the top wall of the channel when the pipe is rotated in the channel. 50
- 15 5. In a regenerative furnace comprising a group of regenerator chambers arranged side by side and a brickwork channel alongside the regenerator chambers and ports leading from the different regenerator chambers to said channel and formed with orifices adapted to register with said ports, the improvement which comprises yielding 55
- 20 30

projections secured to the pipe and adapted to engage with the wall of the channel and force the pipe laterally into snug engagement with the side of the channel at which said ports open as said pipe is rotated from one position in which said orifices do not register with said ports into a second position in which the orifices register with said ports. 40

6. In a regenerative coke oven comprising a plurality of regenerators arranged side by side and formed with a brickwork channel beneath the regenerators, polygonal in cross section, and having ports leading through its top wall to the different regenerator chambers and having a removable metallic pipe, circular in cross section and loosely received in said channel and formed with orifices adapted to register 50 with said ports, the improvement which consists in projections secured to said pipe and adapted to slide in a lower corner of said channel as said pipe is inserted in and removed from said channel, and adapted to 55 engage the bottom of the channel and cam the pipe against the top wall of the channel when the pipe is rotated in the channel. 60

Signed at New York city, in the county of New York and State of New York, this 28th day of September, A. D. 1918.

LOUIS WILPUTTE.
